UNITED STATES PATENT OFFICE.

GEORGE R. RICH, OF CHICAGO, ILLINOIS.

PISTON FOR INTERNAL-COMBUSTION ENGINES.

1,228,049.

Specification of Letters Patent. Patented May 29, 1917.

Application filed July 10, 1916. Serial No. 108,309.

To all whom it may concern:

Be it known that I, GEORGE R. RICH, a citizen of the United States, and a resident of Oak Park, county of Cook, and State of Illinois, have invented certain new and useful Improvements in Pistons for Internal-Combustion Engines, of which the following is declared to be a full, clear, and exact description.

10 This invention relates to pistons for internal combustion engines, and its primary object is to provide a piston wherein the lower side of the piston head may be insulated thermotically from the intense heat developed at the top of the piston head. It is well known to those skilled in the art to which this invention pertains, that the piston head becomes very hot under the influence of the heat developed from the explosions of the combustible mixtures used in internal engines and that the lubricating oil coming in contact with the under side of the piston head is often "fried" on the underside thereof, whereby its efficiency as a lubricant is destroyed. It has been proposed to provide a hollow space in the piston head to avoid this difficulty, but from my experiments along this line, I have discovered that such a hollow space, unprovided with other 20 heat conducting means, causes the top of the piston head to become so hot as to produce premature explosions. With the present invention the lower face of the piston head is kept comparatively cool and the intense heat at the top of the head is conducted away therefrom and radiated or absorbed by the water-cooled cylinder walls. The invention consists therefore in a piston having a hollow space in its piston head, 30 paralleling the head as well as the piston wall behind the piston rings; furthermore it consists in a piston having a hollow piston head formed with fins cast on the underside of the top of the piston head and extending to the piston wall. The invention further consists in the several novel features hereinafter described and claimed:

The invention is clearly illustrated in the accompanying drawing, in which:—

50 Figure 1, is a central, longitudinal section through a piston embodying one form of the present invention; Fig. 2, is a horizontal section taken on the line 2—2 of Fig. 1; Fig. 3, is a horizontal section taken on the line 3—3 of Fig. 1, and Fig. 4, is a detail

fragmental section taken at the upper corner of the piston.

Referring to said drawing, 10, designates the annular piston wall of the piston, and 11, its head, which in the present instance is 60 illustrated as cast integral with the wall 10, although it is not necessary to cast it integral therewith:

In accordance with the usual practice, the wrist pin bearing bosses 12, are cast on the inner face of the piston wall 10, and the ring receiving grooves are formed in the external face of the wall 10, for the reception of the piston rings 13. The piston head 11, is formed with a cavity or hollow space 14, which extends crosswise of the piston, and at the annular wall of the piston said cavity is continued down behind the piston rings 13, in the form of an annular recess as shown at 15. The top portion 16, of the head, and bottom portion 17, thereof may be parallel with each other if desired, and the hollow space may be wider than the thickness of either top 16, or bottom portion 17. 70 To form the annular portion 15, of the cavity, the bottom portion 17, of the head is formed with a down turned annular wall 18, the lower edge of which is turned outward as at 19, and joins with the annular piston wall 10. The cavity is conveniently formed 75 by casting the piston with a core in the head, and a hollow boss 20, opens out from the cavity through which the core may be removed; said boss 20, is internally threaded 80 and a threaded plug 21, is screwed into the 85 boss to hermetically seal the cavity.

Preferably the air is exhausted from the cavity before the plug is screwed in so as to produce a partial vacuum in the cavity to thereby increase its efficiency as a thermotic 95 insulator between the top and bottom portions of the head.

For conducting away the intense heat developed at the top of the piston head, I provide heat conducting fins or webs 22, upon 100 the underside of the top portion 16, which fins or webs preferably radiate outward from the center of the top portion and merge into the same at the center; the fins are increased in height near the annular wall and their lower edges merge thereinto. Said fins are spaced away from the bottom portion 17, to guard against heat being conducted to said bottom portion; said fins are cast 105 integral with the top portion and act to con- 110

duct much of the intense heat to the annular wall 10, of the piston, from which it is absorbed by the water-cooled cylinder wall of the engine. Furthermore the bottom portion 17, will be kept comparatively cool because of the cavity between it and the top portion; when a partial vacuum is maintained in the cavity its efficiency as a thermic insulator is increased. By reason of the cooled bottom portion 17, the lubricating oil splashing against said bottom portion is not subject to the deleterious effect of a hot piston head.

More or less variation of the exact details of construction is possible without departing from the spirit of this invention; I desire, therefore, not to limit myself to the exact details of construction shown and described, but intend in the following 20 claims to point out all of the invention disclosed herein.

I claim as new and desire to secure by Letters Patent:—

1. A piston for internal combustion engines, having a hollow piston head, the hollow space being completely inclosed and there being fins in the hollow space, formed on the underside of the top portion and extending to the annular wall portion of the 30 hollow head.

2. A cast metal piston for internal combustion engines, having a hollow piston head cast with radially extending fins in the hollow portion, the hollow space being completely inclosed and said fins extending down from the underside of the top portion of the hollow head and their lower edges merging into said top portion and into the annular wall of the piston head.

40 3. A piston for internal combustion en-

gines, having an annular wall open at the bottom and a hollow piston head, the hollow space being completely inclosed and the head being formed with heat conducting fins on the top portion of the hollow head, said fins being located in the hollow space.

4. A piston for internal combustion engines, having a head formed with an isolated cavity extending to the annular wall 50 of the piston and then down along the inside thereof in the form of an annular recess, there being one or more annular ring receiving grooves in the external face of said wall outside of said annular recess.

5. A piston for internal combustion engines, having a piston head formed with an isolated hollow space, the hollow space being carried down along the inner side of the annular piston wall in the form of an annular space, and there being radially extending heat conducting fins formed on the underside of the top portion of said hollow head and extending to the annular wall of the head.

6. A piston for internal combustion engines, cast with a hollow piston head having a partial vacuum therein.

7. A piston for internal combustion engines, having a vacuum chamber in its head.

8. A piston for internal combustion engines, having an isolated hollow space in its head formed by an integral wall paralleling the face of the head and a portion of the annular wall, said piston having piston ring 75 receiving grooves formed in the external face of said wall outside of said hollow space.

GEORGE R. RICH.
